[57] CLAIM

The ornamental design for a lawn pool target frame, substantially as shown and described.

DESCRIPTION

FIG. 1 is a top plan view of a lawn pool target frame showing my new design;

FIG. 2 is an end elevational view;

FIG. 3 is a side elevational view;

FIG. 4 is a bottom plan view;

FIG. 5 is a top plan view similar to FIG. 1, but showing a modified form of the design;

FIG. 6 is an end elevational view of the design of FIG. 5;

FIG. 7 is a side elevational view of the design of FIG. 5.
